UNITED STATES PATENT OFFICE

JOSEPH A. DELANEY, OF JERSEY CITY, NEW JERSEY

WINDOW SCREEN

Application filed March 31, 1931. Serial No. 526,735.

This invention appertains to new and useful improvements in window screens and more particularly to a metallic slidable window screen.

5 The principal object of this invention is to provide a metallic window screen wherein the frame is composed of sections, welded, soldered or brazed together at their ends to provide a frame which can be cheaply manufactured and which in use will be exceedingly durable.

Another important object of the invention is to provide a window screen wherein the screen sheet is securely fastened in place.

15 Still another important object of the invention is to provide a window screen of light construction and capable of being assembled in a quick and convenient manner.

During the course of the following specification and claim, other important objects and advantages will become apparent to the reader.

In the drawings:—

20 Figure 1 represents an inside elevational view of the screen.

Figure 2 represents a fragmentary outside elevational view of the screen.

Fig. 3 represents a sectional view taken substantially on the line 3—3 of Fig. 2.

25 Fig. 4 represents a fragmentary section taken on substantially the same line of Fig. 2 as is Fig. 3, but without the retaining strip.

Fig. 5 represents a fragmentary perspective view of one of the retaining strips.

30 Fig. 6 represents a fragmentary outside elevational view disclosing a pair of the frame sections about to be joined together.

Fig. 7 represents a fragmentary detailed sectional view taken substantially on the line 40 7—7 of Fig. 2 and showing a corner of the frame after the connection ends have been welded together.

Fig. 8 represents a fragmentary detailed sectional view disclosing a split type rivet for securing the retaining strip in place.

Fig. 9 represents a fragmentary side elevational view of the screen with the retaining strips spot-welded in place.

45 Referring to the drawings wherein like numerals designate like parts, it can be seen

in Fig. 1, that the frame is constructed of four sections, each denoted by numeral 5. As is clearly shown in Fig. 3, the section is provided with a plane 6 and at one longitudinally edge portion is bent laterally and inwardly to provide the guide channel 7. The sheet of material of which the section 5 is constructed is further disclosed to provide the front side 8 which has its inner part disposed obliquely in an inward direction as at 9. The inner longitudinal edge portion of the plane side 6 is disposed inwardly as at 10 and then extended as at 11. The edge portion of the extended part 11 is bent outwardly as at 12, thus providing a trough for the reception of the edge portion of the window screen sheet 13'.

50 As is clearly shown in Fig. 4, the obliquely disposed portion 9 is extended to a position against the extension 11 as at 13, and is then disposed along the outer side of the laterally disposed portion 12 as at 14 and over the edge portion thereof to project into the aforementioned trough as at 15. Thus the longitudinal edge portions of the sheet of metal of each section 5 are brought together in an interlocking union to provide a trough for the reception of the edge portion of the screen sheet 13'.

55 In the form of the invention shown in Figs. 1 to 4 inclusive, the portions 13 and 11 are provided with registering openings 16 through which bolts 17 are disposed. These bolts extend through the retaining strip 18 and are equipped with nuts 19, so that when 60 the edge portions of the screen 13' are disposed into the troughs aforementioned, the inward pressure of the retaining strips 18 against the same will serve to draw the screen taut and the strips are retained in 65 this position by the nuts 19.

70 The foregoing describes a metallic screen wherein the screen sheet is readily replaceable. In Fig. 9, it can be seen that the strip 18 can be secured in place for retaining the 75 screen sheet 13' by spot-welding, soldering or brazing at the points 20, or at other suitable points.

78 At this point in the specification, it is 80 desirable to call the reader's attention to the 85 100

joining of the sections 5 together at the corners of the frame by welding, brazing or soldering. These methods of securing the ends are both economical and insures durability. This type of joint is clearly shown in Fig. 7 wherein the welded part is denoted by numeral 21.

Fig. 6 discloses the sections preparatory to the act of welding, brazing or soldering 10 the ends together.

As is shown in Fig. 8, as a substitute for the bolts and nuts as well as the spot-welding 20 in Fig. 9, the use of split rivets 22 is desirable. The split rivet is constructed so 15 that the solid shank portion 23 is of sufficient length to extend entirely through the portions 11, 13 as well as the screen sheet 13' and retaining strip 18. This is desirable as it eliminates any crevice into which water 20 can settle, and result in rust and deterioration.

It will be observed, that a window screen frame constructed in accordance with the above specification will be both light and durable, durable because of the manner in which 25 the corners are secured, principally by welding, brazing or soldering, or fusing in any other suitable manner or method.

Furthermore, the manner in which the retaining strip is disposed with respect to the screen involves a practical advancement in the art and insures durability and staleness in view of the overlapping and interlocking construction of the inner longitudinal 35 edge portions of the metal sheets making up the frame sections.

While the foregoing specification sets forth the invention in specific terms, it is to be understood that numerous changes in 40 the shape, size and materials may be resorted to without departing from the spirit and scope of the invention as claimed hereinafter.

Having thus described my invention, what I claim as new is:—

45 A window screen comprising a metallic frame, each member being formed of a single strip of material bent to form a pair of side parts and an edge part having a channel therein, the inner edge of one of the side 50 parts being bent to form a channel and the opposite side part having its inner portion bent obliquely towards the other side part and then at an angle to form a wall which is in alignment with the outer wall of the second 55 mentioned channel, the parts being then bent to contact the bight part of the second mentioned channel and then bent into hooked shape over the inner wall of said channel to connect the edges of the strip together, a 60 screen sheet fitting over the frame with its edges entering the inner channel of the members thereof, strips in said inner channels for holding the edges of the screen sheet therein and fasteners passing through the strips, the 65 parts of the screen sheet located in the chan-

nels, the bights of said channels and the aforementioned part which contact said bight parts.

In testimony whereof I affix my signature.
